UNITED STATES PATENT OFFICE.

CARL EICKEMEYER, OF YONKERS, NEW YORK.

GAS-RANGE.

SPECIFICATION forming part of Letters Patent No. 784,391, dated March 7, 1905.

Application filed October 4, 1904. Serial No. 227,128.

To all whom it may concern:

Be it known that I, CARL EICKEMEYER, a citizen of the United States, residing in Yonkers, in the county of Westchester and State of New York, have invented certain new and useful Improvements in Gas-Ranges, of which the following is a specification.

This invention relates to certain improvements in gas-ranges, which are designed with a view of combining in one single structure an effective broiler, an oven at one or both sides of said broiler, a water-heater, and the ordinary cooking-burners, said range having the advantage of being also adapted to be used for heating purposes during the winter season; and for this purpose the invention consists in the combination in a range of a casing, spaced horizontally-aligned ovens supported therein, and a broiling-chamber arranged between said ovens and of greater height than the same.

The invention consists, further, in the combination in a range of a broiling-chamber having a top opening, a cover-plate for the latter, and an auxiliary plate for coöperating with said cover-plate in positioning a broiler in said broiling-chamber.

The invention also consists in other novel features and combinations of parts to be hereinafter described and claimed.

In the accompanying drawings, illustrative of one embodiment of the invention, Figure 1 represents a front elevation of a gas-range with one broiling-chamber and two ovens. Fig. 2 is a vertical longitudinal section of the same on line 22, Fig. 3. Fig 3 is a plan view of my improved gas-range, showing the top plate removed from the left half of the range. Fig. 4 is a vertical transverse section on line 44, Fig. 1. Fig. 5 is a plan view of the gravy-collecting pan. Figs. 6 and 7 are respectively a plan view and a side elevation of the covering-plate for the broiling-chamber, and Figs. 8 and 9 are respectively a plan view and side elevation of an auxiliary top plate to be placed over the covering-plate for holding the handle of the broiler-frame in a central position during the broiling operation.

Similar letters of reference indicate corresponding parts.

Referring to the drawings, *a* represents the exterior casing of my improved range-broiler. The casing *a* is supported on legs *b*, which are made of suitable height so as to support the range conveniently for use. The cast-iron front wall *d'* of the casing *a* is provided at the lower part with perforated ears *e*, cast integral therewith for forming the hinge connection with the front doors *a⁸* and *a¹⁰* for the ovens and for the front door *c'* of an intermediate broiling-chamber arranged between said ovens. The front wall *d'* is also provided at its upper part with lugs *e'* for supporting these front doors when in closed position in the same manner as in the ordinary stoves. The rear wall *a²* is likewise made of cast metal and provided with flanges *a³* *a⁴*, one at the lower and one at the upper part, for making connection with the uptake-pipe *s*', that leads to the chimney. The side walls *a⁴* are made of sheet metal in one integral piece with the bottom *a⁵*, said one-piece side walls and bottom resting on inwardly-projecting flanges *a¹¹* of the front wall *d'* and rear wall *a²* and being retained by the downwardly-projecting end flanges *d'* of the top *d*, which latter is made of cast-metal plate and provided with the usual lid-openings *u'*, below which the burners *u* for the cooking vessels are arranged. The front and rear walls are connected at their lower corners by transverse bolts *f*, tightened by means of screw-nuts *f'*, applied to the threaded front ends of the bolts, as shown in Figs. 1 and 3. The parts of the exterior casing are thus rigidly connected together and can be assembled readily by the simple tightening of the nuts *f'* of the bolts *f*.

At the inside of the casing *a* are arranged two ovens *o* and *o'*, which are made of sheet metal and so arranged that their top, side, and bottom walls are equidistant from the respective top, side, and bottom walls of the casing. When two ovens are used, they are both preferably made of one continuous piece of sheet metal, as shown in Fig. 2—that is to say, they are made by bending up at each end the piece of sheet metal from which they are to be made so as to form two rectangular bodies which abut at their ends against the front and rear walls of the casing *a*. The so-

- formed ovens are held in position and supported by flanges a^6 , projecting inwardly from the front and rear walls of the casing, as shown clearly in Fig. 2. The short end flanges o^8 of the one-piece sheet metal from which the ovens are formed are riveted to the bottom wall of the ovens, so that thereby the ovens form one connected structure, which is securely held between the front and rear walls of the casing a by the surrounding flanges a^6 . To the side walls of the ovens at the inside of the same are attached angle-irons o^3 , adapted to support intermediate shelves o^4 , should such be desired, for heating plates or other culinary purposes.
- The ovens o and o' are arranged at such a distance from each other that a broiling-chamber c of sufficient width is arranged between them for receiving the broiler and the heating appliance for the same. The broiling-chamber c is provided with a hinged front wall c' and a covering-plate h , (shown in Fig. 6,) which is supported on flanges h' of the top plate d . The covering-plate h is provided with parallel inwardly-extending slots h^2 , into which the handles t of the broiler t' are placed when the latter is placed in position in the broiling-chamber. The covering-plate h is further provided with a registering pin h^3 , by which connection with a second auxiliary plate h^4 of approximately square shape is made, which auxiliary plate h^4 is provided with a registering hole h^6 , adapted to be engaged by the pin h^3 . The auxiliary plate h^4 is also provided with slots h^7 , arranged in a direction at right angles to the slots of the covering-plate h , as shown in dotted lines in Fig. 6, so that by the intersection of the two parallel slot systems the handles of the broiler are held firmly in position. The covering-plate, as well as the auxiliary plate, is provided with small lugs h^9 and h^{10} , which abut alongside of each other and hold the cover-plates in position.
- At the sides of the broiling-chamber are arranged horizontal gas-supply pipes m , provided with openings m' for the heating gas-jets. The pipes m are connected at their rear ends with an upright manifold m^2 in communication with the gas-supply and provided with a stop-cock m^3 for turning on the gas, the spindle m^5 of the same passing through the top plate and being provided at its upper end with a handle m^4 . An air-opening in the supply-pipe of sufficient size produces the mixing of the air with the gas supplied, so that jets of blue flame are issued from the holes of the gas-supply pipes m for heating the meat, toast, or other article to be broiled.
- In the bottom of the broiling-chamber is arranged a gravy-collecting pan p , which is shown clearly in Fig. 5 and which is provided with a central lug p' , that registers with a socket-opening p^2 in the rear wall of the casing. Side lugs p^2 are also provided, which

register with corresponding openings in the side walls of the ovens, so as to place the collecting-pan p into properly-centralized position in the broiling-chamber. The front of the collecting-pan is provided with a curved tubular outlet p^3 , that conducts the gravy collected in the pan p into a cup i , which is supported on a bracket a^8 , located on and cast integral with the front wall of the casing a . The gravy-collecting pan p is provided at opposite sides at the interior of the pan with inclined lugs p^4 , by which the lower end of the broiler resting thereon is placed in central position between the heating-jets, so that a uniform broiling heat is exerted from both sides on the articles placed in the broiler. A recess is arranged in the front door c' of the broiling-chamber, which serves in connection with the inclined lugs p^4 of the collecting-pan p for positively holding the pan in central position in the bottom of the broiling-chamber, so that it is enabled by its inclined side lugs to support the lower part of the broiler centrally in the broiling-chamber between the gas-jets, while the handle of the broiler is supported by the main and auxiliary cover-plates centrally on the top plate of the broiling-chamber.

The ring-shaped burners n , that are located below the openings of the top plate d , are constructed in the same manner as in the gas-ovens heretofore in use and supplied with gas by suitable branch supply-pipes $n^x n^2 n^3$, extending from the upper part of the casing to the front part thereof and then back to the main supply-pipe, said branch supply-pipes being provided with the usual stop-cocks $n^4 n^5$. The openings for the cooking vessels are closed when not in use by means of lids n^6 in the same manner as in the ordinary cooking stoves or ranges.

Above the gas-supply pipes in the broiling-chamber is arranged a U-shaped water-pipe l , which is connected at one front end with a suitable water-supply l' and at its other front end with an outlet water-pipe l^2 . The inlet and outlet water-pipes may be provided with suitable stop-cocks, (not shown,) so as to regulate the supply of water. The pipe l is located close to the gas-supply pipes m in the broiling-chamber, so as to be heated by the heat of the same. If desired, the upper gas-supply pipes of the broiling-chamber may be separately supplied from the lower ones, so that the water can be heated independently of the broiling operation by simply lighting the jets of the upper gas-supply pipes and shutting off the lower ones, two separate stop-cocks being in such case provided.

At each side of the broiling-chamber is arranged between the top plate and the upper corner of the ovens a hinged and weighted damper-plate s , so as to permit on opening one or both damper-plates the products of combustion to pass around the ovens to the

lower part of the same and through the lower opening s^3 to the pipe s' , that takes them to the chimney, thereby heating the ovens. When this heating of the ovens is not required, the 5 dampers are both closed, as shown in Fig. 2, and the heat and the products of combustion from the broiler pass through the upper opening s^4 directly to the pipe s' , and so to the chimney. The products of combustion of the 10 ring-shaped burners for cooking vessels are likewise conducted around the oven, so that not only the surplus flame of the same is utilized for cooking purposes, but also for heating the ovens, thereby also heating the air of the 15 room in which the gas-range is placed.

My improved gas-range can also be used with a single oven by cutting off the left or right hand oven and the corresponding portion of the top plate and casing. By this arrangement a smaller and cheaper gas-range 20 can be provided.

The advantages of my improved gas-range are as follows: The broiler instead of being arranged horizontally or vertically, as heretofore, is arranged centrally between or alongside of the ovens, whereby a very effective heating action on both sides of the article to be broiled is obtained, making it possible to complete the broiling in about one-half the 25 time than hitherto. The heat of the products of combustion led around the ovens is used for heating the same, whereby a uniform baking heat is produced thereon and at the same time an effective room-heater is provided.

30 A further advantage is that the gravy produced by the broiling falls into the gravy-pan instead of on the burners, as hitherto, causing thereby an unequal heating-surface of the same and a clogging of the burner-holes.

40 By the combined construction of the gas-range from cast metal and sheet metal a compact construction offering advantageous features in manufacturing is produced which enables the manufacturer to furnish the gas-range at a rate to compete with the ordinary 45 gas-ranges of similar sizes now in use, while having greater advantages than the same.

I claim as new and desire to secure by Letters Patent—

50 1. In a range, the combination of a casing, spaced horizontally - alined ovens supported therein, and a broiling-chamber arranged between said ovens and of greater height than the same.

55 2. In a range, in combination, a casing, spaced ovens supported therein, the top of each oven being spaced from the top of the casing, and a broiling-chamber arranged between said ovens and extending above the same.

60 3. In a range, in combination, a casing, spaced ovens supported therein and having the bottoms thereof formed by a strip extending between the same, the top and sides of each oven being likewise formed by said strip, 65 and a broiling-chamber arranged between said

ovens and having the bottom thereof constituted by the intermediate portion of said strip and the top thereof constituted by the top of the casing.

4. In combination, in a range, a casing, 70 spaced ovens supported therein, the top of each oven being spaced from the top of said casing, and a broiling-chamber arranged between said ovens and having the top thereof constituted by the top of said casing. 75

5. In combination, a casing, spaced ovens supported therein, and a broiling-chamber arranged between said ovens and having the top thereof constituted by the top of the casing, the latter being provided with a top opening 80 for said broiling-chamber.

6. In a range, in combination, a casing provided with a top opening, a broiling-chamber in said casing below said opening, and a free cover-plate for the latter provided with means 85 for positioning a broiler in said broiling-chamber.

7. In a range, in combination, a casing provided with a top opening, a broiling-chamber in said casing beneath said opening, and a free 90 cover-plate for the latter adapted to maintain a broiler in upright position in said broiling-chamber.

8. In combination, in a range, a broiling-chamber having a top opening, a cover-plate for the latter, and an auxiliary plate for co-operating with said cover-plate in positioning a broiler in said broiling-chamber. 95

9. In combination, a broiling-chamber having an opening, a cover-plate for the latter, 100 and an exterior auxiliary plate for co-operating with said cover-plate in positioning a broiler in said broiling-chamber.

10. In combination, a broiling-chamber having an opening, a cover-plate for the latter 105 provided with slots for engaging a broiler to position the same in said chamber, and means arranged exteriorly of said casing for retaining the broiler against movement in said slots.

11. In combination, in a gas-range, a broiling-chamber, a top plate for covering the same and for engaging a broiler so as to prevent the displacement of the same in one direction, and an auxiliary plate in connection with said top plate for preventing the displacement of 115 the broiler in a direction at right angles to the first-named direction.

12. In combination, in a range, a broiling-chamber having a top opening, a cover-plate for the latter provided with slots for engagement with a broiler, and an auxiliary plate for maintaining the broiler against movement in said slots. 120

13. In combination, a broiling-chamber having an opening, a cover-plate for the latter 125 provided with slots for engagement with a broiler, and an auxiliary plate likewise provided with slots for co-operating with said first-named slots in positioning a broiler in said chamber. 130

14. In combination, a broiling-chamber, a top plate for the chamber having slots, and an auxiliary plate registering therewith having slots at right angles to the slots of the first plate.
15. In combination, a broiling-chamber, a broiler, a gravy-pan supporting the latter and centering the bottom of the same in the broiling-chamber, and a top plate positioning the handles of the broiler centrally of the broiling-chamber.
16. In a gas-range, the combination, with a casing, of spaced horizontally-aligned ovens supported therein, each oven being spaced from the walls of said casing, heating means between the top of each oven and the top of the casing, a broiling-chamber between said ovens and having the top thereof constituted by the top of the casing, means for heating said broiling-chamber, and a damper arranged in the space between the top of each oven and the top of the casing.
17. In a gas-range, the combination, with a casing, of spaced horizontally-aligned ovens supported therein and each spaced from the walls of the casing, heating means between the top of each oven and the top of the casing, a broiling-chamber arranged between said ovens, means for heating said broiling-chamber, and an uptake communicating with said casing below said ovens and said broiling-chamber.
18. In a gas-range, the combination of a casing, ovens supported at the interior of said casing transversely to the front and rear walls of the same, a broiling-chamber between said ovens, gas-supply pipes adjacent the side walls of the broiling-chamber, flues extending around the ovens, and dampers located in said flues at their connection with the broiling-chamber.
19. In a gas-range, the combination, with a casing, of spaced horizontally-aligned ovens supported therein, each oven being spaced from the walls of said casing, heating means between the top of each oven and the top of the casing, a broiling-chamber between said ovens and having the top thereof constituted by the top of the casing, means for heating said broiling-chamber, dampers in the space between the top of said ovens and the top of the casing, and an uptake communicating with said casing below said ovens and said broiling-chamber.
20. In a gas-range, the combination, with a broiling-chamber provided with gas-supply pipes at opposite sides thereof, of a gravy-collecting pan at the bottom of the same, means for supporting said gravy-collecting pan centrally in the broiling-chamber, means on said collecting-pan for centering the broiler when placed in position therein, a top plate provided with slots for the handles of the broiler, and an auxiliary plate provided with slots extending at right angles to the slots of said top plate for holding the wire handles of the broiler firmly in central position in the broiling-chamber.
21. In a range, the combination, with a broiling-chamber, of a gravy-pan supported at the bottom thereof, said pan being provided with an outlet-tube for centering the same in the broiling-chamber, and at opposite sides thereof with retaining-lugs, and a cover for the broiling-chamber provided with slots, the lugs of said gravy-pan and the slots of said cover being adapted to coöperate in positioning a broiler in said broiling-chamber.
22. In a gas-range, the combination, with an exterior casing provided with a plurality of front doors and openings in its top for the cooking vessels, and gas-burners below said top openings, of ovens in said casing, a broiling-chamber between said ovens, gas-supply pipes at both side walls of the broiling-chamber, flues extending from the broiling-chamber around the ovens, an outlet-opening in the casing below the broiling-chamber, an outlet-opening in the casing above the gas-supply pipe of the broiling-chamber, dampers at the point of connection of the upper part of the broiling-chamber with said flues, and a pipe connecting with the outlets in the broiling-chamber for conducting off the products of combustion.
23. A gas-range, comprising a casing, ovens supported transversely to the casing, having their top, bottom and side walls arranged substantially equidistantly from the respective top, bottom and side walls of the casing, said ovens being made of one continuous piece of metal, heating means in the casing between the top of the oven and top of the casing, lid-openings in the top of the casing above said heating means, a broiling-chamber arranged between the ovens, the adjacent walls of the latter forming the side walls of the broiling-chamber, heating means in the broiling-chamber, and an uptake-pipe connecting with the upper and lower part of the casing.
- In testimony that I claim the foregoing as my invention I have signed my name in presence of two subscribing witnesses.
